TICKET ISSUER FOR PINBALL GAMES

Raymond T. Moloney, Chicago, Ill.

Application April 2, 1935, Serial No. 14,314

4 Claims. (Cl. 271—2.4)

The present invention relates to an improvement in a ticket issuing device for use with pin ball games, the played balls serving, when trapped, to close switches which close circuits to control operation of motor means to operate the ticket issuer.

More particularly the invention is an improvement over the structure shown in my co-pending application filed jointly with Milton N. Tigerman on January 23, 1935, Serial Number 3,036 for a Ticket issuing device for pin ball games.

These pin ball games embody a play board presenting a surface inclined from the horizontal, said board having holes therethrough to trap balls rolled over the surface. Skill in the playing of the game is developed by repeated playing thereof and to encourage as much play as possible, since the games are coin released, it is desirable to offer an award commensurate with the skill displayed. By the present invention it is proposed to pay off in tickets which have a given value which entitles the player to receive from the location owner, coins or tokens, that may be used in the game for releasing the same for further play. Each ticket may have printed thereon its value, such for example as the legend "Good for two free games". It is desirable to make the ticket award commensurate in value with the degree of skill displayed; in other words, greater skill to receive a greater award, and lesser skill to receive a proportionately smaller award.

In my prior application the ticket dispenser embodied a motor operated slide which operated connections, including a swingable lever and hook engageable in perforations in the tickets to issue or dispense the same. Also the slide controlled a circuit for operating a solenoid to actuate a knife to sever from the ticket band the tickets to be issued.

In the present improvement the motor operated slide operates a structurally different ticket issuing means and also a different type of ticket severing mechanism.

Accordingly, it is the primary object of the invention to provide mechanism associated with a game of this type which will operate to dispense or issue one or more tickets of stated values as an award for skill demonstrated in the playing of the game.

Another important object of the invention is to provide such ticket issuing mechanism which embodies a ball controlled electric timer for governing the operation of a mechanical ticket issuer.

Still another object is to provide such means

in a simple compact form so that it will be efficient and fool proof in operation.

It is also an important object to provide means that will be operative automatically to issue one or more tickets in accordance with the skill displayed in playing the game.

A further object is generally to provide a ticket issuing device for coin released pin ball, and the like, skill games for amusement purposes.

Other and perhaps equally important objects of the invention will no doubt become clear to those skilled in this art as the disclosure is more fully made.

Briefly, the improved game of skill comprises a cabinet containing a play board inclined slightly from the horizontal and having formed therein a number of holes, each designated with a certain numerical value, and adapted to receive balls projected over the board. Switch means is arranged under each score hole so that a ball entering the holes remains supported by the switch means and closes a circuit to initiate operation of an electric means, such as a motor, which in turn operates the improved ticket vending and severing mechanism. The ball controlled circuit closing mechanism may be so arranged that a predetermined number of traps must have received a ball before the dispensing mechanism can become operative. A commutator control is operative from the motor to regulate the time of effectiveness of the circuits closed, whereby the dispenser member may make one or more passes or strokes before being stopped. In this way the number of tickets issued is proportioned to the skill displayed. The setting of the dispenser control mechanism and of the game parts is preferably controlled by a coin released slide.

A practicable form of the invention is shown in the accompanying drawings, wherein:

Figure 1 is a general plan view of a type of pin ball game with which the improved ticket issuer may be employed;

Figure 2 is an electric diagram to illustrate the control means for the motor that causes operation of the ticket vender;

Figure 3 is an enlarged, central longitudinal sectional view through the game, showing the ticket issuer, as viewed along the line 3—3 of Figure 1, looking in the direction of the arrows;

Figure 4 is a fragmentary, detail side sectional view, illustrating the ball elevating mechanism, taken along the same line 3—3 before mentioned, but looking in the opposite direction;

Figure 5 is a detail, transverse sectional view taken along the line 5—5 of Figure 3, looking in

the direction of the arrows, to show the manner of assembling the game board in the cabinet to establish certain electrical circuits;

Figure 6 is an enlarged plan view of the ticket issuing mechanism per se mounted in position in the game cabinet;

Figure 7 is a side elevational view of the ticket vending mechanism shown in Figure 6;

Figure 8 is a plan view of a section of the ticket band to illustrate the form of the tickets vended;

Figure 9 is a transverse sectional view through the ticket vending mechanism taken along the section line 9—9 of Figure 6, looking in the direction of the arrows; and,

Figure 10 is a longitudinal sectional view through the ticket issuing mechanism taken along the line 10—10 of Figure 6, looking in the direction of the arrows.

As shown in Figures 1 and 3 the game with which the improved ticket vender may be used, comprises a cabinet 10 having an open top closed by a glass panel 11. The cabinet includes a front wall 12 and a floor 13. The game board is shown at 14, the same being sloped from the horizontal in the usual manner with its lower end adjacent the front wall 12. This board carries a raised member 15, providing an oval track 16 at the upper and lower ends of the board to guide balls in the usual way. Balls are projected by a spring plunger 17, through the passage 18 onto the upper end of the board 14, such balls being guided by the edge 16 to a spring bumper 19 from which they rebound onto the play surface for gravitation down the board.

Thirteen ball receiving holes, in this embodiment of the game, are arranged in the board 14 to receive skillfully projected balls, such holes being preferably arranged in aligned pairs, for the purpose, as will later appear, of controlling the manner of operation of the ticket, or pay off vender. For example, the first pair of holes is designated 20 and 21; the second pair 22, 23; the third pair 24, 25; the fourth pair 26, 27; and the fifth pair 28 and 29. The holes in each pair are transversely aligned, as shown. A longitudinally aligned pair of holes 30, 31 is also provided; and at the upper end of the board is provided what may be termed a master or control hole 32.

In playing the game, as will later appear, to attain a ticket pay off it is necessary first to trap a ball in both holes of any one of the pairs of holes described, and thereafter another ball must be lodged in the control hole 32 to establish the necessary circuits to operate the vender. Or the ball trapping may be in any order; however, before the ticket vender can work, a ball must be in the hole 32, and in both holes of any of the pairs of holes described. A ball missing these holes gravitates to the lower edge of the board 14 to be guided into the pocket 33, which may be termed an out ball pocket.

Underneath the board 14, the side walls of the cabinet 10 carry guide brackets 34 for slidably mounting an inclined thin ball release panel 35, normally pulled toward the front wall 12 by a spring 36. The lower edge, or front end of this panel is thus normally disposed under the out ball pocket 33 to support the spent balls therein as shown in Figure 3. Said panel 35 is formed with a number of rather long lengthwise slots 36 equal in number to the ball receiving holes formed in the board 14 and respectively positioned with respect to said holes to cause release of the balls from the game board holes when

the panel 35 is slid or shifted rearwardly by means of the usual coin released slide 37 slidably carried in the front wall 12 of the cabinet, said panel 35 having a shoulder 38 thereon to be abutted by the inner end of the slide 37 in the manner well understood in these games, for the purpose stated.

A switch device is carried on the under side of the board 14 rearwardly of each ball receiving hole in the game board, such switches being generally shown in the diagram of Figure 2 and being respectively designated 20', 21', 22', 23', 24', 25', 26', 27', 28', 29', 30', 31', and 32'; the switches 31' and 32' being shown in detail in Figure 3.

These switches are all structurally alike and as shown in Figure 3 the switch arms 31' and 32' are normally horizontally disposed between the board 14 and panel 35, said arms being pivotally connected by hinge pins 39 to clips 40 secured to the under side of the board 14. These arms 31' and 32', and in all of the other switches too, extend under the respective holes as shown in connection with holes 31 and 32, said arms resting on the panel 35 adjacent the slots 36 therein. Overlying each switch arm is a spring contact bar 41 normally gapped away from the switch arm and carrying an insulated plate 42 which is located in the respective hole, as shown. Switch contacts are carried on the switch arms and under the spring bars, so that when a ball enters a hole, its weight causes engagement of these contacts, with the ball remaining supported on the plate 42 until subsequently released as will later appear.

Looking at Figures 2, 3, and 5 it will be seen that the upper end of the board 14, on its under side carries a plate 43 carrying seven transversely spaced, depending, contact posts 44, each post 44 being detachably in engagement with seven respective metal clips 45 mounted on the rear wall 40 of the cabinet 10.

As shown in Figure 2, and reading from left to right, a wire 46 is connected between the post 44 and the spring arm of switch 32'; a wire 47 similarly connects the second post 44 with switch 21'; a wire 48 with switch 23'; a wire 49 with switch 25'; a wire 50 with switch 27'; a wire 51 with switch 29'; and, a wire 52 with switch 30'. Further, a wire 47' connects between the pair of switches 20' and 21'; a wire 48' between switches 22' and 23'; a wire 49' between switches 24' and 25'; a wire 50' between switches 26' and 27'; a wire 51' between switches 28' and 29'; and a wire 52' between switches 30' and 31'. All these wires 47', 48', 49', 50', 51', and 52', the latter through switch 31', connect with a wire 46'. The circuit wire 46, 46' constitutes the main power line as will later appear. All of these wires are preferably mounted on the under side of the game board as indicated in Figure 3.

Wires 47a, 48a, 49a, 50a, 51a, and 52a lead respectively from six of the clips 45 in engagement with six of the posts 44 as shown in Figure 2, to respective brushes 47b, 48b, 49b, 50b, 51b, and 52b mounted on an insulated plate 53, the wires leading to these brushes being suitably arranged in the lower part of the cabinet 10. A seventh brush 54 is also carried by the plate 53, said brush 54 being connected by a wire 55 with a motor 56 and a battery 57 in turn connected with the end post 44 connected with the main power line 46, 46'. The battery 57 is suitably mounted on the floor 13 of the cabinet 10 at its 75

rear end, while the motor 56 is carried on a base 58 located in back of the front wall 12.

The brush 54 always engages the edge of a metallic commutator drum 58 turnable with a shaft 59, said drum being covered with an insulated cover 60 formed with a spirally arranged set of cut outs of varying lengths, numbered 47^a, 48^a, 49^a, 50^a, 51^a, and 52^a, respectively in line, to cooperate with the brushes 47^b, 48^b, 49^b, 50^b, 51^b, and 52^b.

From the structure thus far described it will be seen that an important feature, from the manufacturing standpoint, resides in the fact that the board 14 on its under side carries half of the circuit wires and that the board 14 with its switches and wires can be separately assembled as a unit. Similarly the lower portion of this electrical mechanism can be separately assembled in the cabinet as a second unit. By merely setting the assembled board unit in place in the cabinet the circuits are completed above and below when the posts 44 are placed on the clips 45.

The motor 56 has a shaft 61 carrying a worm gear 62 in turn driving a worm wheel 63 journaled on a shaft 64 supported on a bracket 65 as shown in Figures 3 and 9. This transverse shaft 64 has fixed to an end thereof, a wheel 65' carrying an eccentric pin and roller 66. This roller is operable in a vertical slot 67 formed in an upright wall 68 formed on a horizontal slide member 69 suitably guided on the base 58. This slide moves longitudinally back and forth as will later appear.

The walls 68 of the slide 69 carries a pivoted spring pressed pawl 70 to engage a ratchet wheel 71 fast on the shaft 59 to turn the drum 58 in a step by step manner, said turning movement of the drum winding a spring as in my co-pending application identified and being held from reverse turning movement by a suitable dog as in the previous application. A lever 71' controlled by the coin slide 37 releases such dog to permit the force of the wound spring to return the drum 45 to an initial starting position. This mechanism per se forms no part of the present invention and reference is therefore made to the co-pending application for a more detailed showing and description of these parts.

The wall 68 also has connected to it a forwardly extending link 72, having its front end connected to a crank 73 pivotally carried on a shaft 74 journaled in a bracket 75. The crank 73 pivotally carries a pawl 76 engageable with a ratchet wheel 71 also carried on the shaft 74. This ratchet wheel 71 may be secured to one side of a vertical drum wheel 78 loose on the horizontal shaft 74, said wheel depending below the board 14 into a pocket 79 as shown in Figure 10 and having on its periphery, transversely aligned pins 80 arranged in equi-distantly, spaced pairs.

This pin wheel 78 is located at the rear end of a channel shaped sheet metal housing or frame 81 secured on the floor 13 adjacent the base 58, the top of this housing carrying an upper guide strip 82 having its rear end curved for a portion of its length in close, but spaced relation around the quadrant peripheral portion of the wheel 78, said strip having spaced slots 83 to accommodate the pins 80 which project therethrough. A lower guide strip 84 is also provided as shown, and between these two strips is passed a band of tickets 85 in strip form, the band coming from a storage reel 86 suitably carried on a support 87 as shown in Figure 3. The

band of tickets is provided at equi-distantly spaced intervals with aligned pairs of perforated holes 88, which receive the pins 89 so that the wheel 78 when it rotates may positively advance the tickets in a forward direction between the 5 guide strips 82, 84 in an obvious manner. The tickets each have printed thereon a suitable legend, such for example, as "Good for two free games".

A wall 89 is carried on the housing 81 which 10 wall with the parts 82, 84 and a bar 90, terminates flush to form a shear edge adjacent the throat 91 formed in a dispensing chute 92 in front of the ticket issuer and leading to an opening 93 formed in the front wall 12 of the cabinet, 15 said chute including a depending ticket deflector 94 as shown best in Figure 10.

As appears in Figures 6 and 9 the wall 89 is bent laterally to form a cross wall portion 95 on which is pivotally mounted a knife 96 pressed by a spring 20 97. The knife, which is a lever, includes an extension 98 cooperable with a trip lever 99 pivoted intermediate of its ends on the wall 95. The other end of the trip lever 99 engages a pin 100 on the lower end of a vertical plate 101 having slots there- 25 in receiving pins 102 on the wall 95 to guide the plate 101 for free vertical sliding movement on the wall.

The lower edge of the plate always rests by gravity on the periphery of a cam wheel 103 turn- 30 able with the shaft 64, heretofore described. The cam wheel 103 is timed in its operation to cause the spring pressed knife 96 to operate at the proper time, said cam wheel having a low notch 104 to cause the plate 101 to drop suddenly, where- 35 by to release the lever 99 and make the spring pressed knife 96 operative, in an obvious manner. This knife moves down alongside the flush end of the parts 82, 84, and 90, a shear guide 105 being provided for causing proper operation of the 40 knife.

When the balls are released from the holes in the board 14 they pass through the slots 86 and onto a lower ball routing board 106 stationarily mounted on brackets 107 on the side walls of the 45 cabinet. (See Figure 3.) At the lower edge of this board 106 is a transversely inclined trough 108 to receive the balls. Balls dropping from the pocket 33 fall onto an inclined chute member 109 and are thus also led to the through 108. 50

As appears in Figure 4 the trough 108 inclines toward an arcuate groove 110 formed in the right hand wall of the cabinet 10 from whence they may be elevated by a pivoted lifter 111, of usual form, operable by a plunger 112, into the passage 55 18 to be placed in position to be projected by the plunger 17 onto the board 14 to be trapped by the holes.

The dispenser control slide 63 carries a pin 113 to which is connected a spring 114 having its 60 other end connected to a post 115 mounted on the stationary base plate 58. The control and operating parts 53, 56 are carried on the base 58 as has been stated and the ticket dispenser is jointly carried on this base 58 and a sub plate 13'. In 65 this manner the entire unit may be separately assembled and be placed on the floor 13 as a complete unit assembly. This facilitates manufacture.

In playing the game it will be assumed that all balls are in the trough 108. These balls are ele- 70 vated in the manner described to be projected one at a time by the plunger 17. The balls then gravitate from the high end of the board toward the low end to be trapped in the holes formed therein. We will assume that the first two balls 75

so played are received in the holes 20 and 21. These balls are then held by the switches 20', 21' in visible position in the said holes, and weighting down the spring contact elements there-
5 in to close the said switches 20', 21'. Thereafter, if the next ball played is lodged in the master hole 32 to close the switch 32' we find a circuit from the battery, through all three switches, the commutator 58, to the motor 56 and back to the battery is completed.

10 This circuit is through wires 46, 46', 47', 47, 47', to commutator brush 47^b, contact 47^c, brush 54, wire 55, motor 56 and back to the battery 57. With the motor now operating, the gearing 62, 15 63, turns shaft 64, and eccentric wheel 65' to move the slide 69. Movement of the slide operates the link 72 to operate the pawl 76, ratchet wheel 71 and drum 78. Turning of the drum, of course, moves the ticket web to advance the web toward the chute 92, the issuing end of the web contacting the deflector 94 in an obvious manner. Simulta- 20 neously, the ratchet wheel 71 is turned by its pawl connected to the slide wall 68 to move the contact 47^c out of engagement with the brush 47^b thereby breaking the circuit. The motor is thus stopped, but just before this happened the shaft 64 turned the cam wheel 103 to a point where it will be stopped, when the motor is cut off, to cause the slide 101 to drop off the cam shoulder 104. 25 This permits the spring pressed knife lever 95 to swing downwardly to sever one ticket from the ticket band, said ticket being good for two free plays, and dropping down the chute 92 to the discharge opening 93. The first commutator contact 47^c is, in other words, just long enough to permit one ticket to be issued.

30 In the same way as clearly shown by Figure 2, if two balls are now lodged in the pair of holes 22, 23, a circuit 48, 48', 46', 46, is established to the motor and commutator contact 48^c through brush 48^b, wire 48^a, commutator 58, brush 54 and wire 55. The contact 48^c is twice as long as contact 47^c and as a result the motor operates twice as long to cause the slide 68 to make two complete strokes and as a result the drum 78 is turned enough to cause issuance of two tickets, the knife controlled by its cam making a cut for each ticket in an obvious manner.

35 In the same way the holes 24, 25, when receiving balls, cause circuits clearly shown in Figure 2 to operate the motor long enough to issue three tickets. The holes 26, 27 will cause five tickets to be issued. The holes 28, 29 will cause eight tickets to be issued; the holes 30, 31 will cause ten tickets to be issued.

40 Balls missing the switch holes are received in the out ball pocket 33 and are taken out of play. When the predetermined number of balls have been played, these balls will be in the switch holes and some perhaps in the out pocket. The commutator drum will have wound its spring which is held locked wherever the drum stops in its rotation.

45 To replay the game the coin slide 37 must be operated. This shifts the panel 35 to release the balls from the switches. As the panel is shifted the hinged switches drop into the respective slots 36 to permit the balls to roll therefrom through the slots 36 and onto the ball routing panel 106 for return to the trough 108. The balls from the pocket 33 also return to said trough 108 in the manner described. When the slide 37 is released the spring 36 pulls the panel 35 to its forward position, said panel moving the switches back into ball receiving positions under the respective holes.

50 The movement of the coin slide 37 also operated the trip lever 71' to release the dog that held the commutator drum, whereby its energized spring drives it reversely to its starting position as shown in Figure 2, with the brush 47^b on the contact 47^c.

55 From this detailed disclosure it can now be seen that an improved ticket vender and an improved pin ball control means therefor has been provided, which achieves all of the desirable objects heretofore recited.

60 It is the intention to cover all such changes and modifications of the preferred example chosen for this disclosure which do not in material respects constitute departures from the spirit and scope of the invention as covered by the appended claims.

65 What is claimed is:

1. The combination with a motor driven reciprocatory slide member carried on a floor 20 formed with an opening adjacent an end of the slide member, of a ticket dispenser comprising a bracket mounted on the floor adjacent said opening, a horizontal shaft mounted in the bracket over the opening, a pin wheel rotatable 25 about the axis of the shaft and extending part way downwardly into said opening, a guide for a ticket web arranged in close curved overshot relation to the wheel and extending tangentially therefrom over the floor to guide a ticket web to 30 a point of discharge, said pin wheel being located at the charging end of the guide to push the web therethrough, a ratchet turnable with the pin wheel, a crank arm independently turnable on the shaft and carrying a pawl in operative relation to the ratchet, and an operating link pivotally interconnected between the crank arm and slide member.

35 2. In a ticket dispenser comprising a horizontal floor formed with an opening in which is positioned a rotary pin wheel on a horizontal shaft located above the floor, the combination therewith of an elongated housing mounted on the floor and extending from the pin wheel and including spaced horizontal strips at its top between which is adapted to be guided a ticket web trained over the pin wheel from a source of supply, said strips extending from the wheel to a point of discharge for the tickets, a motor driven slide mounted on the floor adjacent the 40 housing and located between the point of discharge and the drum, a ratchet wheel coaxial with the shaft and turnable with the pin wheel, a crank swingably mounted on the shaft including a pawl to engage the ratchet wheel to move 45 the pin wheel intermittently in a direction to draw the web from the source of supply and push the free end thereof through the guide strips to the point of discharge, and an operating link pivotally connected between the crank and motor driven slide member, said link being movable exterior of and alongside said housing.

50 3. In a ticket dispenser for a cabinet having a vertical wall and a horizontal floor with the wall having a discharge opening, the combination therewith of an elongated substantially rectangular housing carried on the floor substantially at right angles to the wall and having one end registering with the opening, said housing along its top including a pair of horizontal flat 55 guide strips spaced apart to form a passage for a ticket web, a pin wheel journaled on a horizontal axis and located at the end of the housing remote from the wall, one of said guide strips being curved downwardly in overshot relation to 60

the wheel so that a ticket web may be guided from a source of supply over the wheel and into the space between the guide strips, and means for turning the wheel in a step by step manner 5 to cause it to push the free end of the web through and between the horizontal guide strips toward the opening in said wall.

4. In a ticket dispenser for a cabinet having a vertical wall and a horizontal floor with the 10 wall having a discharge opening, the combination therewith of an elongated substantially rectangular housing carried on the floor substantially at right angles to the wall and having one end registering with the opening, said housing 15 along its top including a pair of horizontal flat guide strips spaced apart to form a passage for

a ticket web, a pin wheel journaled on a horizontal axis and located at the end of the housing remote from the wall, one of said guide strips being curved downwardly in overshot relation to the wheel so that a ticket web may be guided 5 from a source of supply over the wheel and into the space between the guide strips, means for turning the wheel in a step by step manner to cause it to push the free end of the web through and between the horizontal guide strips toward 10 the opening in the wall, said guide strips terminating short of said wall and opening, and an inclined chute at the terminal end of said guide strips to direct the discharging end of the web through said opening at substantially floor level. 15

RAYMOND T. MOLONEY.
